SAFETY RAZOR

Fred J. Mehl, Wichita, Kans., assignor, by direct and mesne assignments, of thirty-seven and one-half per cent to Ulysses G. Charles, and twenty-five per cent to Guy C. Boling, both of Wichita, Kans.

Application June 18, 1941, Serial No. 398,554

2 Claims. (Cl. 30—43)

This invention relates to a safety razor, and more particularly to a razor having a motor actuated blade, and has for its principal object a blade having two cutting edges oppositely disposed, each edge having a single guard substantially in parallelism with the edges of the blade, or the edge of the guard and its respective edge of the blade may be nonparallel, whereby a shearing movement of the blade is means to cut beard more easily and beginning at one end rather than to cut the entire length of the blade simultaneously.

A further object of this invention is to provide a razor for dry shaving, and by rocking movement of the body of the razor will engage one edge at a time as the razor is moved in its slanting direction with respect to the body or handle of the razor, and by an erect position with respect to the surface being shaved, both edges will function simultaneously to avoid omission that otherwise may occur with a single edge engagement.

A still further object of this invention is to provide a scissor contact for the entire length of the blade as it moves along the surface of a growth of beard.

A still further object of this invention is to provide a simple and efficient means to remove and replace the cutting blade and furthermore to provide a simple and efficient means for oscillatory movement of the blade by the rotation of a single drive shaft, whereby the blade is moved longitudinally and transversely along a circular path.

A still further object of this invention is to construct a power-driven safety razor that will produce a mild massage for the face as the head of the razor is moved thereover, and the razor as a whole being simple, economical to construct, and efficient in its performance.

These and other objects will hereinafter be more fully explained, reference being had to the accompanying drawing, forming a part of this specification, and in which like characters will apply to like parts in the different views.

Referring to the drawing that forms a part of this specification, attention is first directed that the motive power, whether electric or otherwise mechanically driven, has been omitted for convenience of illustration, but will be applied at the discretion of the manufacturer with respect to the style of the motor, and inasmuch as the invention of this application resides in the structural parts of the shaving head as disclosed, note:

Fig. 1 is a cross section of the head elements,

taken on line 1—1 in Fig. 3, showing each cutting edge of the blade engaging beneath its respective guard element.

Fig. 2 is a side view of the head, while Fig. 3 is a plan view thereof.

Fig. 4 is a cross section taken on line 4—4 in Fig. 3.

Fig. 5 is a similar view to that of Fig. 1, showing the ends of the guard above the blade as retaining means therefor, while the side edges are adapted to engage above their respective side guard, and Fig. 6 is a cross section taken on line 6—6 in Fig. 5, showing the edges of the blade in one relative position of the guards or terminal 15 of the side walls, the shaft and gears being in elevation.

Fig. 7 is a cross section through a blade and blade carrying plate as modified.

Fig. 8 is a similar sectional view to that shown in Fig. 1 except modifying the method of driving 20 the blade carrying plate.

Fig. 9 is an inverted plan view taken on line 9—9 in Fig. 8, looking in the direction of the arrows.

Fig. 10 is a modification for the carrying plate to secure the blade against longitudinal and transverse displacement when the razor is in action.

Fig. 11 is a sectional view taken on line 11—11 in Fig. 10.

Fig. 12 is a modification of the securing means to the carrying plate, parts removed for convenience of illustration.

Fig. 13 is an end elevation of the head, where in the guard structure is hinged at one side to rock from engagement with the blade and carrying plate therefor.

The following is a detailed description of the constituent parts of this invention, consisting of a body portion 1, the motor containing portion of which is removed, while the other portion, converging from the body with respect to its sides, contains the elements of the shaving head, a portion of which is integral with the body, consisting of side walls 2 and having formed at its outer extremity a gear housing comprised of outer and inner walls 3 and 4 respectively, said walls being spaced apart and having positioned therebetween a master gear 5 secured to the end 45 of a drive shaft 6 that is journalled in wall 3, while wall 4 has an opening A through which said gear 5 will pass for convenience of assembly, and the said gear being in mesh with a pair of gears 50 7 oppositely disposed with respect to the dia-

metrical axis of gear 5, last said gears being journaled in the said housing walls 3 and 4.

Secured to the journal of each of said pairs of gears is a disc 8 seating closely on the outer wall, the diameter of which is sufficient to position a pin 9 eccentrically thereon with respect to the journal axis, said pins each being trunnioned in a carrying plate 10 for oscillatory movement thereof as said discs are rotated with their respective gears 7, the said carriage plate being the carrying means for a shaving blade 11 seated thereon, said blade having oppositely disposed cutting edges B that extend longitudinally of the blade. The said carriage has a pin 12 spaced inward from each end thereof and being on the center axis of the carrying plate with respect to cross section, and extending outward from the upper side of the carrying plate, said blade having an aperture therethrough at each of its ends corresponding with the pins to engage thereon as securing means for the blade against longitudinal and transverse movement as the carrying plates move; and furthermore said blade is retained against outward or upward movement by the ends C of a guard 13 engaging thereover, said portion C being arced inward as shown in Fig. 3 as a means to permit engagement of the entire length of the cutting edges. In other words, the terminal ends of the blade cutting edges to be in close proximity to the ends of the head. Otherwise, the guard consists of divergent side walls to coincide with the convergence of the head and being secured thereover by screws 13', the ends of the guard being in parallelism as shown in Figures 1 and 2.

Along each side of the guard at its outer extremity is an integrally joined flange D extending inward toward each other, the inner extremity of each adapted to coact with the cutting edges of the blade to cut beard, as said beard enters between the blade edges and their respective flanges, and furthermore said flange to function as a guard to avoid cutting of a patron during the course of shaving.

It will be seen in Figs. 4 and 6 that the cutting edges of the blade may be arranged to engage below or above the flanged guard, and when positioned above the guard the flange extension for the side may be omitted as shown in Fig. 6; in case of the latter the carrying plate may be omitted and the blade increased in thickness, if so desired. However, in either case, the face is well protected as the upper extremity of the guard and side of the blade coact as safety elements against the cutting edges of the blade; and furthermore, the space between the blade edges and their respective guards is comparatively narrow at the maximum point of separation, but open sufficient for the beard of the face to enter therebetween, it being understood that the cutting process takes place at each edge of the blade alternately and under high velocity of movement.

In Figs. 8 and 9 is illustrated a method of moving a carrying plate 14 by the drive shaft, in which instance said shaft has a disc 15 secured to the end thereof and on which is eccentrically positioned a pin 16, said pin engaging in an aperture centrally positioned in the carriage as shown at E in Fig. 9, the eccentric sweep of which is indicated by dotted lines F in said figure. It will be seen that this arrangement will eliminate the said gear housing and gears. In lieu of the housing, there is positioned a wall 17, said wall having a pair of cylindrical

pins 18 upwardly extending and integrally joined to the wall, each pin being equally spaced outward from the drive shaft in diametrical alignment therewith, and each adapted to engage in their respective aperture 19 that is correspondingly positioned in the carriage, said apertures being of greater diameter than that of the pins to allow for the eccentric stroke of the disc pin, whereby said carriage is rocked with an oscillatory movement while the said pins 18 will restrict against opposite rocking movement of the ends of the carriage as the shaft turns.

Note that the carriage is modified to carry the blade, the modification being to provide a lip 20 extending upward at each end of the carriage, between which the ends of the blade will snugly engage to avoid longitudinal movement as the carriage moves, and the said lips each have a transversely positioned lip 21 at each end thereof, said portions at the upper extremity to conform to the bevel of the blade as shown in Fig. 11; the ends being thus seated, will avoid transverse movement of the blade, it being understood that the arced extension of the guard as shown in Fig. 3 is means to avoid upward or outward movement of the blade as the arced portion extends well over its respective end of the blade.

In Fig. 12 is shown a modified method to secure a blade 22 to a carriage 23, the carriage having an arced shoulder G at each end thereof between which the arced ends of the blade 22 will engage, coinciding with the shoulder. Positioned on each shoulder is a headed pin 24 eccentrically pivoted and adapted to turn to and from engagement with the blade as a simple and efficient means to secure the blade, in which instance, the head of the pin will be concealed by the inward arc of the guard but not in contact therewith.

In Fig. 7 is shown a modified form for a razor blade 25, the sides of which are convex, while the carriage seat for the blade is concavo to coincide with the blade, and to avoid longitudinal or transverse movement of the blade during oscillatory movement there is positioned near each end of the carriage 26 a pin 27 rigidly secured and adapted to engage in an aperture through the blade correspondingly, the blade being secured against upward movement by the arcuate ends of the guard engaging thereon.

In Fig. 13 is shown a modification for the guard 28 in which case the body portion of the guard has been decreased in depth and hingedly connected at one side as at H to rock to and from engagement with the end of the head, and being secured, when rocked to engagement, by a ball and socket arrangement as shown at K on the side opposite the hinge, and such other modifications may be made as lie within the scope of the appended claims.

Having fully described this invention what is claimed as new, and desired to secure by Letters Patent is:

1. In a safety razor, a hollow body portion comprised of side and end walls, a drive shaft trunnioned in the body, an elongated blade substantially rectangular in form and having two cutting edges oppositely disposed and positioned longitudinally of the blade, a carriage plate for the blade, and means to move said plate and blade longitudinally and transversely in circular motion, said means being actuated by the said shaft, and a guard carried by the body portion, said guard having a portion in parallelism with

each edge of the blade coating therewith to shear as the edges of the blade alternately pass with close engagement with their respective portion of the guard.

2. In a safety razor, a hollow body portion comprised of side and end walls, a drive shaft trunnioned in the body, a blade substantially rectangular in form and having two cutting edges oppositely disposed, a carrying plate for the blade, a series of gears actuated by the shaft, 10 a portion of said gears being connected to the

blade carrying plate by pins eccentrically carried by said gears to oscillate the plate, said plate carrying said blade therewith, a guard and means to removably secure the guard to the body portion, said guard having a rectangular opening at its outer extremity and being in registry and equaling in width to that of the blade with respect to its cutting edges whereby the edges of the blade will alternately engage their respective sides of the guard as the blade oscillates.

FRED J. MEHL.
